UNITED STATES PATENT OFFICE.

FREDERICK W. GERHARD, OF REDFIELD, SOUTH DAKOTA.

CARD-INDEX TRAY.

No. 903,855.

Specification of Letters Patent.

Patented Nov. 17, 1908.

Application filed June 15, 1908. Serial No. 438,649.

To all whom it may concern:

Be it known that I, FREDERICK W. GERHARD, a citizen of the United States, residing at Redfield, in the county of Spink and State of South Dakota, have invented a new and useful Card-Index Tray, of which the following is a specification.

This invention relates to card index trays or drawers, and while primarily designed for containing index cards such as usually employed in card systems; yet it is to be understood that the article is equally well adapted for containing various kinds of papers, checks and the like.

The object of the invention is to provide a tray or drawer of the character described including a novel form of follower or locking device, the same being wholly disconnected from the bottom of the tray or drawer and capable of being readily moved throughout the length thereof, and removed if desired, whereby access to the contents of the drawer may at all times readily be effected and whereby, further, owing to the peculiar construction of the follower any binding or locking of the same within the tray, will positively be obviated.

With the above and other objects in view, as will appear as the nature of the invention is better understood, the same consists in the novel construction and combination of parts of a card index tray or drawer as will be hereinafter fully described and claimed.

In the accompanying drawings forming a part of this specification and in which like characters of reference indicate corresponding parts,—Figure 1 is a view in perspective, partly in section, of a card index tray or drawer embodying the features of the present invention. Fig. 2 is a perspective detail view of the follower or locking member. Figs. 3, 4, 5, and 6 are views in front elevation of four modified forms of followers.

The tray or drawer 1 may be made of any suitable material, preferably of wood, and of any size required. While it will generally be designed to employ the tray for containing index cards such as are commonly used in card index systems, and as shown in Fig. 1, yet it is to be understood that it may be utilized for holding various kinds of papers, and as this will be readily understood, detailed illustration thereof is omitted.

As shown, the tray or drawer is rectangular in shape and its interior, that is to say,

its bottom, sides and ends are devoid of any projecting parts, such as guides or the like, as are generally employed in connection with articles of this character. Secured to the upper edges of the sides are two keepers 3 that extend inward toward each other any desired distance and are designed to hold in position a follower designated, generally, 4. This follower, which may be constructed of any suitable material, preferably wood, on account of its lightness and cheapness, comprises a head plate 5 and a clamping member 6, the two being commensurate in length and thickness. The member 6 is held assembled with the head plate or member 5 by a pair of upstanding guide rods 7 that are preferably rigid with the member 5 and engage transverse orifices 8 in the member 6. In order to cause the member 6 to be forced away from the member 5, coiled springs 9 are mounted upon the guide rods and bear at their opposite ends upon the upper edge of the member 5 and on the under edge of the member 6.

Instead of employing the coiled springs shown in Fig. 2, a flat bow-shaped spring 10 may be adopted, as shown in Fig. 3, and this may be secured either to the under edge of the member 6 or the upper edge of the member 5, as may be preferred.

In the use of the device the index cards or other papers are disposed against one end, and the follower is then moved toward this end, the member 6 being depressed in order to permit it to pass under the keepers 3, and as soon as the head plate is properly positioned relatively to the cards or the like, pressure is removed from the member 6, whereupon the coiled springs shown in Fig. 2 or the bowed spring shown in Fig. 3 will cause the member 6 to engage with the under faces of the keepers 3, and thereby lock the follower firmly in position. When it is desired to inspect the papers held between the follower and one end of the box, the member 6 is depressed and the follower is drawn backwards the required distance to loosen the papers to permit easy examination thereof.

Instead of constructing the follower with straight ends, as shown in Figs. 4, 5, and 6, the ends of the clamping member 11 may be provided with rabbits 12, as shown in Fig. 4, to straddle the keepers 3; or the two members 13 and 14 of the follower may each be provided with terminal extensions 15 and

16, as shown in Fig. 5, either of which pair
of extensions may engage with the under
faces of the keepers; or the clamping mem-
ber 17 alone may be provided with terminal
5 extensions 18, as shown in Fig. 6, to engage
with the under faces of the keepers.

The improvements herein defined while
simple in character, will be found thor-
oughly efficient for the purposes designed
10 and owing to the simplicity of construction
of its parts, will materially reduce the cost
of manufacturing such articles, and also
overcome any tendency of the follower to
stick or bind within the tray or drawer.

15 What is claimed is:—

A card index tray or drawer having in-
ward projecting keepers secured to its upper
edges, in combination with a two-part fol-
lower, and resilient means arranged between
the members of the follower to cause one of 20
them to engage the under faces of the
keepers.

In testimony that I claim the foregoing as
my own, I have hereto affixed my signature
in the presence of two witnesses.

FREDERICK W. GERHARD.
